(57) **CLAIM**

I claim the ornamental design for a coffee table, as shown and described.

DESCRIPTION

FIG. 1 is a perspective view of a coffee table showing my new design;

FIG. 2 is a top plan view thereof;

FIG. 3 is a right side elevational view thereof, the left side elevational view being identical to the right side elevational view;

FIG. 4 is a front elevational view thereof, the rear elevational view being identical to the front elevational view; and,

FIG. 5 is a bottom plan view thereof.
